Primary Examiner — S. Bryan Reinholdt, Jr.*Assistant Examiner* — James T Tyree(57) **CLAIM**

The ornamental design for a LED saber, as shown and described.

DESCRIPTION

FIG. 1 is a front and right perspective view of a LED saber, showing my new design;

FIG. 2 is a rear, left, and bottom perspective view thereof;

FIG. 3 is a front elevational view thereof;

FIG. 4 is a rear elevational view thereof;

FIG. 5 is a left elevational view thereof;

FIG. 6 is a right elevational view thereof;

FIG. 7 is a top plan view thereof;

FIG. 8 is a bottom plan view thereof;

FIG. 9 is an enlarged view of the delineated region 9 in FIG. 1; and,

FIG. 10 is an enlarged view of the delineated region 10 in FIG. 1.

The dot-dash broken lines in FIGS. 1, 9, and 10 form no part of the claimed design and delineated portions of the claimed design that are shown on an enlarged scale in FIGS. 9 and 10. The dashed broken lines in FIGS. 1, 2, 3, 8, and 9 depict portions of the LED saber that form no part of the claimed design.

1 Claim, 10 Drawing Sheets(56)
